UNITED STATES PATENT OFFICE.

JOHN E. LAYTON, OF PITTSBURG, PENNSYLVANIA.

IMPROVED BACK PLATE AND CHIMNEY-THROAT FOR FIRE-PLACES.

Specification forming part of Letters Patent No. 33,591, dated October 29, 1861.

To all whom it may concern:

Be it known that I, JOHN E. LAYTON, of Pittsburg, in the county of Allegheny and State of Pennsylvania, have invented a new and useful article of manufacture, consisting of a Combined Back Plate and Throat-Piece for Open Fire-Places; and I do hereby declare the following to be a full, clear, and exact description thereof, reference being had to the annexed drawings, forming part of this specification, in which—

Figure 1 is a representation of an open fire-place, showing by dotted lines the application of my improvement. Fig. 2 is a transverse vertical section of the fire-place shown in Fig. 1. Fig. 3 is a perspective representation of my combined back plate and throat-piece.

In the construction of fire-places and chimneys nothing is more important than the construction and situation of the throat of the chimney and the relative position of the back wall of the fire-place thereto.

Many fire-places smoke just because of some slight defect in the construction or location of the throat of the chimney, and there is a great deal of heat wasted in open fire-places for want of a correct position to the back wall of the fire-place. This is owing in a great measure to a want of skill and knowledge in the mechanics who are employed to build chimneys and set grates, and especially is this the case in country places.

As the comfort of a house depends so largely on the means of heating it, and a fire-place with which a room may be easily warmed is a matter of great importance, I have contrived a back wall and chimney-throat combined in one piece, which may be set by any brick-layer, however unskilled in the art of building fire-places, and which will not only cause a chimney to draw well, but will greatly increase the amount of heat given out from a fire over the ordinary method of construction.

In order to enable others skilled in the art to construct and use my improvement, I will proceed to describe it more fully.

In the drawings, Fig. 3 represents my combined throat-piece and back wall for open fire-places. It is made of cast-iron in a single piece. *a* is the back plate, consisting of a flat rectangular plate of the desired width of

the fire-place. At its upper edge is the throat-piece *b*, the sides of which are parallel. The throat-piece is of the same width as the back plate *a*, the aperture being long and narrow. The sides of the throat-piece and the back plate are set at such an angle to each other as that when in place the back plate will slope more or less upward from the rear wall *c* of the fire-place to the front wall *d*, and the aperture of the throat will incline upward and backward from the front wall of the chimney, as seen in Fig. 2. These combined throat-pieces and back plates will be made of various widths to suit the various sizes of fire-places and chimneys.

The mode of applying my throat-piece and back plate is seen in Fig. 2. It is built into the brick-work in setting the grate in such manner as that the front edge of the aperture of the throat-piece shall touch the front wall of the chimney or arch of the grate just above or on a level with the top of the opening of the fire-place, the aperture of the throat inclining thence upward and backward. There being a space in the rear of the back plate *a*, and also above and in front of the throat-piece, the air in those spaces becomes heated and rarefied by the heat communicated to the back plate and throat-piece by the fire, which causes an upward draft in the chimney sufficient to secure its drawing well. These combined throat-pieces and back plates are designed to be made independent of any other part of the fire-place or grate as an article of manufacture, and to be inserted in the chimney in the manner described for the purpose of improving the draft of the chimney and of increasing the quantity of heat thrown out from the fire into the room.

Having thus described my improvement, what I claim as my invention, and desire to secure by Letters Patent, is—

The construction of a throat-piece and back plate for open fire-places combined in one piece as a new article of manufacture.

In testimony whereof I, the said JOHN E. LAYTON, have hereunto set my hand in presence of two witnesses.

JOHN E. LAYTON.
